(57) **CLAIM**

The ornamental design for a portable vaporization device, as shown and described.

DESCRIPTION

FIG. 1 is a front perspective view of an embodiment of the portable vaporization device;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The broken lines depict portions of the portable vaporization device that form no part of the claimed design. The oblique lines on the portable vaporization device surfaces indicate that those surfaces are transparent.
